UNITED STATES PATENT OFFICE.

MAURICE BREAU AND GEORGES BERTHIER, OF CHATELLERAULT, FRANCE, AS-
SIGNORS TO BERNARD ROMAIN, OF PARIS, FRANCE.

LOCK.

Application filed December 6, 1921. Serial No. 520,399.

To all whom it may concern:

Be it known that we, MAURICE BREAU and GEORGES BERTHIER, both citizens of the French Republic, residing, both, at Chatellerault, Vienne, France, the former at 12 Rue Saint-Jacques, the latter at 170 Grande Rue, have invented a new and useful Improvement in Locks; and we do hereby declare the following to be a full, clear, and 10 exact description of the same.

This invention relates to a locking device enabling locking or blocking any movable organ, such as a clutch lever, or similar part, and applicable also to doors, windows, 15 drawers, and the like.

In order that the invention may be fully understood and readily carried into effect, a specific embodiment of the same will now be described more particularly, by way of 20 example, reference being had to the accompanying drawings, in which:

Figure 1 is a longitudinal elevation of the device.

Figure 2 is a plan-view, partially broken, 25 of the latter.

Figure 3 is a side-view, partially broken, thereof.

Figures 4, 5, 6 and 8 illustrate certain details of construction hereinafter referred to.

Figure 7 is a sectional view on line A—B of Fig. 6; and

Figure 9 is an end view of the key.

As shown in said drawings, this locking device consists of a casing 1 having variable 35 shape and dimensions, the side 2 of which is provided with two apertures 3 and 4 allowing the passage of the locking-bolt. Two suitable key-sleeves 5 and 6 are fastened upon the plates 7 and 8 for enabling the 40 insertion of a key 9. In each of these sleeves 5 and 6 is located a slotted part 10, Figs. 6 and 8, of suitable dimensions, provided with a variable number of wards 10', each said slotted part being permanently kept in its 45 normal position by a coil—or like spring 11. Between the two key-sleeves 10 is placed a worm 12 of suitable shape and dimensions, in both ends of which are provided two sockets 13 and 14. This worm 12 meshes 50 with a helically grooved nut 15 internally threaded, as at 15' and into which is threaded a locking-bolt 16 provided with two noses 17 and 18 passing through the apertures 3 and 4 of the casing side 2.

From the above description the operation 55 of the device will be readily understood.

The key 9, the end of which has pins 23, 24 to fit into sockets 13 and 14 of the worm ends 12, is inserted into the key-sleeve 5 or 6 by pushing it well up to the bottom, so 60 that the slotted part 10 is forced inward by projection 19 of the key (see Fig. 8), and presents itself with its wards opposite the grooves 20' of the stationary dovetailed member 20, thus permitting rotation of part 65 10, and of the key and worm 12.

The thrust of the slotted part 10 is terminated when the bearing 21 of the key abuts against the washer 22 of the sleeve. At this moment, the two pins 23, 24 of the key enter into the sockets 13, 14 of the worm 12. By rotating this worm by means of the key, a rotary motion of the nut 15 is obtained, which latter, being restrained from lateral motion by bracket 15'', actuated the 70 bolt 16 through the medium of its thread and the internal thread 15' of the nut 15.

At each complete revolution, the slot of the slotted part 10 is brought opposite wards 20'' and tends to be pushed by the coil spring 11 to force out the key. As a result, closing 75 by a double or triple revolution, care must be taken to maintain the key pushed up to the bottom in the closing device.

It must be understood that it is possible, 80 without departing from the scope of the invention, to modify the pinions or the toothed wheels, to vary, when required, the lengths of the threaded parts and to increase or decrease the number and the dimensions of the 85 wards of the parts 10 and 20. Moreover, it is obvious that the shape of the closing device and of the locking-bolt can be changed in very numerous manners, and that the key and its operating pins may be of any 90 approved design.

Claims:

1. A lock, comprising a casing, a helically threaded lock bolt in the casing, a threaded nut restrained for rotary motion only, and receiving the threaded bolt, and having helical grooves on its outer periphery, and a key operated, helically threaded worm, in mesh with said nut.
2. A lock as in claim 1, said key operated worm having a key receiving socket, there being an adjacently positioned key way, and a spring pressed ward containing slotted 105

cylinder and a cooperating stationary ward member positioned in the key way, whereby unauthorized manipulation of said lock bolt is prevented.

5. 3. A lock as in claim 1, said key operated worm having key receiving sockets on each side thereof, and a key way positioned on

each side of the worm, each key way containing cooperating ward members.

In testimony whereof, we have signed our 10 names to this specification.

MAURICE BREAU.
GEORGES BERTHIER.
